METHOD OF SKIATRON CLEANUP

Harry C. Kelly, Belmont, Mass., assignor, by
mesne assignments, to the United States of
America as represented by the Secretary of the
Navy

Application December 10, 1945, Serial No. 634,108

10 Claims. (Cl. 315—24)

1 This invention relates to skiatrons or dark trace cathode ray tubes, and more particularly to methods and apparatus for obtaining clean-up of such a tube.

Skiatrons or dark trace cathode ray tubes have the property of retaining patterns or signals which are continually repeated. This condition is known as burn-in, and is often objectionable. When it is desired to apply a different pattern or signal to the skiatron it is usually necessary to clean up the skiatron, that is remove the previously burned-in signals from the screen.

In a known type of optical projection equipment employing a skiatron tube, used as an auxiliary indicator for a radar system, clean-up or erasure of these persistent signals is accomplished by switching to a higher repetition rate, increasing the scan rate, turning down the video supplied to the skiatron, defocusing the electron beam of the skiatron, and removing the heat filter of the optical projection system. By all these steps the skiatron may be cleaned-up, but considerable time was required to achieve clean-up.

It is, therefore, an object of this invention to provide an apparatus for cleaning-up a skiatron which substantially reduces the time required for such clean-up.

A further object is to provide such an apparatus which is simple and inexpensive.

Other objects and advantages of this invention will be apparent from the following specification when taken with the accompanying drawing, the single figure of which schematically represents an embodiment of this invention.

The embodiment shown comprises a skiatron 10 having a screen 11, deflecting means generally designated 12 for providing a radial sweep rotating about an origin on screen 11, and additional means for rapidly cleaning up screen 11. This additional means includes a second source of sweep energy 13 which changes in polarity as well as intensity, and means 14, operative when desired, to connect source 13 to deflecting means 12, whereby the sweep extends diametrically on both sides of the origin, thereby greatly increasing the speed of clean-up of the skiatron. In this particular embodiment the sweep source 13 is a sine wave source.

Also shown in this embodiment are means generally designated 15 for focusing the electron beam of the skiatron, a source 16 of anode voltage for the first anode 17 of the skiatron, means 18 for biasing grid 19 of the skiatron, and means 20 for gating the cathode 21 of the skiatron. The previously mentioned additional clean-up means 55

also include means 22 for defocusing the electron beam of the skiatron, means 23 for reducing the velocity of the electron beam, means 24 for intensifying the electron beam, means 25, 26 for removing cathode gating means 20, and optionally usable means generally designated 27 interconnecting all of these additional clean-up means for simultaneous operation when clean-up is desired. When these clean-up means are operated simultaneously the sweep is formed by an intensified and defocused electron beam on the screen and extends diametrically on both sides of the origin; thereby increasing the speed of clean-up.

The figure shows a projection system which includes all the previously mentioned means, together with an optical projection system generally designated 28 for providing a distant image of the skiatron screen pattern. Optical projection system 28 includes a heat absorber 29 which in normal operation absorbs a portion of the heat from projection lamp 30. Appropriate linkage, here indicated by dotted line 31, removes heat absorber 29 from the optical projection system and permits heat rays from lamp 30 to strike screen 11, thereby heating the screen and increasing the speed of clean-up.

Sweep means 12 comprises sweep coils 32, a source of normal sweep current 33, and rotating means 34 mechanically connected to coil 32, as indicated by dotted line 35. Rotating means 34 turns coil 32, and in combination with source 33 produces a rotating, linearly-increasing magnetic field acting on the electron beam of tube 10. This produces a radial sweep rotating about an origin on the screen. Means 14 comprises a switch to connect sweep coil 32 to either source 33 or, when desired, to source 13.

Focusing means 15 comprises focus coils 36 connected by switch 37 to a D. C. voltage. Current flowing through coil 36 produces a magnetic field of sufficient magnitude to focus the electron beam on the screen 11. When switch 37 is in the lower position resistor 22 is connected in series with the D. C. voltage and coil 36, thereby reducing the magnetic field of coil 36. This results in defocusing the electron beam so that the spot produced on screen 11 is enlarged. In the normal operating condition switch 37 is in the upper position.

Source of anode voltage 16 provides a gating voltage of sufficient magnitude which when applied to anode 17 produces a pulsating stream of electrons which continue on to strike the screen. Switch 38 connects anode 17 to either source 16 or to source 23. Source 23 provides a reduced

D. C. voltage which when applied to anode 17 increases the total number of electrons striking screen 11.

Means 18 for biasing grid 19 comprises a source 39 of D. C. voltage connected by switch 40 to the grid. This D. C. voltage, during normal operating conditions, keeps the tube slightly above cut-off.

Means 24 for intensifying the electron beam of tube 10 comprises a source 24 of decreased bias voltage, which when applied to grid 19 intensifies the electron beam. For normal operation switch 40 connects grid 19 to source 39. For clean-up of the skiatron switch 40 connects grid 19 to source 24.

Means 20 for gating cathode 21 comprises a source 41 of cathode gate voltage which for normal operation is connected by switch 26 to cathode 21. To remove the cathode gating means for clean-up, switch 26 connects cathode 21 by lead 25 to ground.

Means 21 interconnects all of the additional clean-up means for simultaneous operation. This comprises mechanical couplings, designated by dotted lines 42, 43, 44, 45, and 46, for all of the switches and coupling 31 for removing heat absorber 29.

The optical projection means 28 is a conventional Schmidt projection system comprising lamp 30, reflector 41, heat absorber 29, lenses 48, 49 and 50, mirror 54, spherical mirror 51, correcting lens 52 and viewing screen 53. Using this system an enlarged representation of the skiatron pattern is available at viewing screen 53.

When clean-up is desired, switch 14 connects source 13 of sine wave current to sweep coil 32, means 31 removes heat absorber 29 from the optical projection system 28, switch 37 connects resistor 22 in series with focus coil 36, switch 38 connects source 23 of decreased anode voltage to anode 17, switch 40 connects source 24 of decreased bias supply to grid 19, and switch 26 grounds cathode 21. This results in an intensified and defocused electron beam striking screen 11, and produces thereon a sweep which travels completely across the screen instead of starting from the center. This application of electron bombardment, along with heat from the light source 30, removes the burned-in signals in a very short time.

It is to be understood that while this specification has described the theory of the invention as used with a projection system, the invention is not necessarily limited thereto. As is apparent to a person skilled in the art, this invention is applicable to any apparatus employing a skiatron.

What is claimed is:

1. The combination with a skiatron type tube and deflection means for providing a radial sweep rotating about an origin on the screen of the skiatron, of additional means for rapidly cleaning-up the skiatron screen, said means including a second source of sweep energy which changes in polarity as well as intensity, and means, operative when desired, to connect said source to said deflection means, whereby the sweep extends diametrically on both sides of the origin, thereby increasing the speed of clean-up of said skiatron.

2. The combination of claim 1, in which said second source of sweep energy is a sine wave source.

3. The combination with apparatus including a skiatron type tube, a deflection means for providing a radial sweep rotating about an origin on

the screen, means for focusing the electron beam of said skiatron, a source of anode voltage for the first anode of said skiatron, means for biasing the grid of said skiatron, and means for gating the cathode of said skiatron, of additional means for rapidly cleaning-up the screen of said skiatron, said clean-up means including, a second source of sweep energy providing a sine wave, means operative when desired to connect said second source of sweep energy to said deflection means, means for defocusing said electron beam, means for reducing the velocity of said electron beam of said skiatron, means for intensifying said electron beam, means for removing said cathode gating means, and optionally usable means interconnecting all of the aforesaid clean-up means for simultaneous operation when clean-up is desired, whereby the sweep, formed by an intensified and defocused electron beam on the screen, extends diametrically on both sides of the origin, thereby increasing the speed of clean-up of said skiatron.

4. The combination with a skiatron projection system including a skiatron type tube, a deflection means for providing a radial sweep rotating about an origin on the screen, and optical projection means including a heat absorber for providing a distant image of the screen pattern, of additional means for rapidly cleaning-up the screen of said skiatron, said clean-up means including a second source of sweep energy providing a sine wave, means operative when desired to connect said second source of sweep energy to said deflection means, means for removing the heat absorber of said optical projection means to apply heat to said screen, and optionally usable means interconnecting the aforesaid clean-up means for simultaneous operation when clean-up is desired, whereby the sweep, formed on a heated screen, extends diametrically on both sides of the origin, thereby increasing the speed of clean-up of said skiatron.

5. The combination with a skiatron projection system including a skiatron type tube, a deflection means for providing a radial sweep rotating about an origin on the screen, an optical projection means including a heat absorber for providing a distant image of the screen pattern, means for focusing the electron beam of said skiatron, a source of anode voltage for the first anode of said skiatron, means for biasing the grid of said skiatron, and means for gating the cathode of said skiatron, of additional means for rapidly cleaning-up the screen of said skiatron, said clean-up means including, a second source of sweep energy providing a sine wave, means operative when desired to connect said second source of sweep energy to said deflection means, means for defocusing said electron beam, means for removing the heat absorber of said optical projection means to apply heat to said screen, means for removing anode gating voltage, means for intensifying said electron beam, means for removing said cathode gating means, and optionally usable means interconnecting all of the aforesaid clean-up means for simultaneous operation when clean-up is desired, whereby the sweep, formed by an intensified and defocused electron beam on a heated screen, extends diametrically on both sides of the origin, thereby increasing the speed of clean-up of said skiatron.

6. Apparatus for erasing persistent signals from the screen of a dark trace cathode ray tube comprising means for applying heat energy to said screen, means for applying potentials to said

tube to produce an intensified defocused cathode ray beam, and means for applying a sine wave potential to said tube to deflect said beam to provide electron bombardment of said heated screen.

7. The method of erasing persistent signals from the screen of a dark trace cathode ray tube comprising the simultaneous steps of reducing the operating potentials of said tube to produce an intensified defocused beam, applying a sinusoidal sweep voltage to provide electron bombardment of said screen, and applying heat energy to said screen.

8. The method of erasing persistent signals from the screen of a dark trace cathode ray tube having a cathode, a control grid, focusing coils, deflection coils, and an energy sensitive crystal-line screen comprising the steps of reducing the anode potential, reducing the control grid bias potential, and reducing the current in the focusing coils whereby a defocused intensified cathode ray beam is formed, applying a sine wave sweep voltage to said deflection coils whereby electron bombardment of said screen occurs, and applying heat energy to said screen.

9. Apparatus for erasing persistent signals from the screen of a dark trace cathode ray tube comprising means for applying heat energy to said screen, means for applying potentials to said tube to produce an intensified defocused cathode ray beam, means for applying a sine wave potential to said tube to deflect said beam to provide electron bombardment of said heated screen, a switching mechanism, and means operatively connecting said first, second, and third named means to said switching mechanism whereby operation of said switch mechanism simultaneously

applies heat energy and electron bombardment to said screen.

10. In a dark trace cathode ray projection system including a skiatron type tube, deflection apparatus for providing a radial sweep rotating the cathode ray beam about an origin on the screen, and an optical projector including a lamp and a heat absorbing medium for providing a distant image of the screen pattern, apparatus for erasing persistent signals from the screen of said skiatron tube comprising a switching arrangement, means for reducing the potentials applied to said tube to produce an intensified defocused cathode ray beam, means for substituting a sine wave sweep voltage in said deflection apparatus, and means for removing said heat absorbing medium from said optical projector, and means connecting said first, second and third named means to said switching arrangement whereby operation of said switch simultaneously applies heat energy from said lamp and bombardment of electrons to said screen.
